UNITED STATES PATENT OFFICE.

ALVIN HYDER, OF SAN PEDRO, CALIFORNIA.

INTERNAL-COMBUSTION OIL ENGINE.

Application filed November 25, 1918. Serial No. 264,003.

To all whom it may concern:

Be it known that I, ALVIN HYDER, a citizen of the United States, residing at San Pedro, in the county of Los Angeles and 5 State of California, have invented a new and useful Internal-Combustion Oil Engine, of which the following is a specification.

This invention relates to internal combustion engines and more especially to the ignition features thereof.

The invention is not limited to the employment of oil in the operation of the engine and it is understood that the term oil employed herein signifies any fuel suitable 15 for burning in an engine of the semi-Diesel or analogous type of engine.

An important object is to make provision for the scavenging of burnt gases from the hot ball or vaporizer so that a comparatively 20 small amount of fuel injected into said hot ball will maintain the same at suitable temperature for ignition of the fuel.

An object of the invention is to facilitate 25 operating the engine under idling conditions and changing from one condition to the other, especially from the idling to the load condition.

The type of engine shown in the drawings as embodying the invention is the, so-termed, 30 semi-Diesel engine which employs a hot ball or vaporizer and comparatively high compression of the gases, the heat of combustion of the charges of oil and air serving to maintain the vaporizers at the requisite temperature 35 for ignition of the charges when said charges have been compressed by the pistons.

In order to thoroughly understand some 40 of the advantages of this invention, attention is directed to the fact that the semi-Diesel engine operates well under full load, that is to say, that if the engine is working under load all of the cylinders will fire substantially regularly so that the power impulses 45 are delivered to the shaft by the pistons working successively on their power strokes. When the load is removed, for instance when the clutch is thrown out to disengage the driven shaft and its connected load from the engine shaft, quite often one 50 or more of the engine cylinders ceases firing and the idling of the engine is done on the remaining cylinder or cylinders. In this type of engine a torch is employed to initially 55 heat the hot ball sufficiently to cause

ignition of the charge, and it is obvious that when it is desired to put a load on the engine operating at idling speed the hot balls of the inactive cylinders must be heated by their torches or any other suitable means before 60 the cylinders will function. As an example of one use of this type of engine in which it is necessary to have the engine idle frequently and to then pick up the load as quickly as possible may be mentioned its use 65 for propelling fishing boats. It is necessary in the operation of fishing boats that their engines be idled frequently during the casting and hauling in of the fishing nets. Without my improvement it is necessary to 70 heat up the hot balls of the idle cylinders after each stopping of the boat for the casting or hauling in of the nets.

Another object of this invention is to produce evenness of operation of the engine 75 when idling and the avoidance of excessive vibrations.

Other objects and advantages will appear in the subjoined detailed description.

The accompanying drawings illustrate the 80 invention:

Figure 1 is a side elevation of an engine embodying the invention, portions thereof being shown in vertical mid section and other portions broken away for clearness of 85 illustration.

Fig. 2 is an enlarged plan view of the engine cylinders and the ignition mechanism.

Fig. 3 is an enlarged sectional elevation on line indicated by x^3-x^3 , Fig. 2.

Fig. 4 is a plan section on line indicated by x^4-x^4 , Fig. 3.

Fig. 5 is a sectional elevation on line indicated by x^5-x^5 , Fig. 2.

Fig. 6 is an elevation partly in section on line indicated by x^6-x^6 , Fig. 2, the governor and air starting device also being shown in elevation.

The engine shown in Fig. 1 of the drawings, with the exception of the improvements 100 hereinafter to be described, is a Fairbanks-Morse type "C-O" marine oil engine and is illustrated as being provided with three cylinders 1. It is understood that the engine may have two or more cylinders. The engine governor is indicated at 2, the speed control lever at 3, the starting lever at 4, the pump at 5, the fuel pump lever at 6 and the clutch control lever at 7. Each of the cylinders 1 is provided with a piston 8, only 105

one of which is shown in Fig. 1 of the drawings because of the nature of the view.

The upper end of that one of the cylinders 1 shown in section in Fig. 1 of the drawings forms a hot ball or vaporizer 9 into which the charge is compressed on the upstroke of the piston, the vaporizer 9 communicating through a port 10 with the piston chamber 11 of the cylinder. The vaporizer 9 is provided with suitable initial heating means for starting the engine into operation and such means in the instance shown in the drawings comprises a starting tube 12 and a torch 13 adapted to play a flame upon the starting tube to heat the same. The vaporizer 9 is provided with a fuel intake port 14 connected by a fuel pipe 15 to a suitable source of supply. The vaporizer 9 is connected by a tube 16 to a valve chamber 17 provided with a suitable valve 18 which, in the instance shown in the drawings, is in the form of a disk provided with a port 19 adapted when the disk is turned to port-opening position to register with an outlet port 20 in the valve chamber. The valve chamber and its valve may be of any other suitable construction than that shown in the drawings though I have found that the ones described are very satisfactory in operation since the heat does not affect its operation. The stem of the valve 18 is shown at 21 and said stem is turned by a suitable arm 22, there being a spring 23 to hold the valve stem upward so as to hold the valve plate 18 tightly against the upper wall of the valve chamber in order to avoid leakage of gas past the disk valve. A stop 24 is provided in the valve chamber and said stop may be in the form of a screw projecting into the valve chamber and adapted to engage shoulders 25, 26 in the edge of the valve 18 to limit rotative movement of the valve. But one port 19 is shown in the valve 18, but it is understood that if desirable a plurality of ports may be employed and if more than one is employed they will preferably be of different sizes. The parts 14 to 26 inclusive described above for the one cylinder are also employed for each of the other cylinders and those that are visible are designated on the drawings by the same reference characters.

The ports 20 of the valve chambers 17 are connected to one another by tubing 27 which constitutes a chamber for the reception of burnt gases discharged from the vaporizer associated with the cylinder wherein combustion is occurring so that when the valves 18 are turned to open positions communication is afforded between the different cylinders to permit the hot gases to discharge from the chamber 27 into the vaporizers associated with the remaining cylinders.

65 Any suitable means are provided to

simultaneously operate the arms 22 for opening and closing of the valves 18 and said means may be hand-operated if desired. I prefer that the valves 18 be opened and closed automatically by operation of the governor 2 and for this reason the following described construction is provided. Pivoted at 28 to the arms 22 is a rod 29 which is screw-threaded at one end into a tubular slide 30 adapted to reciprocate in a sleeve 31 supported by standards 32 fastened to any suitable support. In the instance shown in the drawings, see Fig. 6, the standards 32 are fastened to the air starter body 33 of the engine. The sleeve 31 is provided diametrically thereof with a pin 34 passing through a slot 35 in the slide 30 and also through a slot 36 in a cam plate 37 which is fastened to one end of a rod 38 that is pivoted at its other end at 39 to the lever 40 of the governor 2 so that operation of the governor will cause movement of the rod 38. The cam plate 37 is adapted to slide through longitudinal slots 41 in the sleeve 31 and through longitudinal slots 42 in the slide 30. The cam plate 37 is provided at its middle portion at opposite edges thereof with slanting faces 43, 44 respectively adapted to bear against the opposite ends of the slots 42, said slot ends thus forming abutments so that up and down movements of the cam plate 37 will cause movements to the left and right respectively of the rod 29 in Figs. 1, 2 and 5 of the drawings, movement to the left causing the valve ports 19 to register with the ports 20 and movement to the right causing the valve ports 19 to be moved out of registration with the ports 20. Speeding up of the governor 2 causes upward movement of the left end of the governor lever 40 in Fig. 6 thus causing opening movement of the valves 18.

The governor lever 40 is connected to a rod 45 which forms a portion of the mechanism for controlling the length of stroke 110 of the pumps 5. This mechanism need not be described herein since it is of well known construction. In this particular engine upward movement of the rod 45 causes shortening of the stroke of the pump plungers 115 so as to cause the pumps to furnish less fuel to the engine cylinders when the speed of the engine increases.

From the foregoing it is seen that there is a direct relation between the fuel supply mechanism and the valve mechanism and that when the fuel decreases in volume the valves 18 open and when the fuel increases in volume the valves 18 close.

The operation of the invention is as follows: Assuming that the engine is not operating and that it is desired to start the same into operation and to operate it at idling speed, the torch 13 will be lighted to heat the vaporizer 9 adjacent thereto. 130

When said vaporizer 9 has been heated to the gas-igniting temperature the starting lever 4 will be operated to admit compressed air to the cylinders, in a manner well understood in the art pertaining to oil engines, thus starting the pistons into operation. Ignition of the charge compressed in the torch-heated vaporizer 9 will occur thus starting the engine into self-operation and 10 the speed of the governor is such as to raise the rod 38 to open the valves 18. The valves 18 being open, whenever a cylinder fires some of the burning gases will discharge from its heated vaporizer 9 through the tubing 27 and valves 18 and tubes 16 of the other cylinders into said other cylinders thus heating the vaporizers and igniting the charge 15 of said other cylinders.

When it is desired to connect the engine 20 with the load, the lever 7 will be operated in the appropriate direction in a manner well understood in connection with this type of oil engine, whereupon the governor, owing to the slowing effect of the load on the 25 engine, will decrease in speed, thus causing an increased amount of fuel to be supplied to the cylinders and at the same time effecting closing of the valves 18. The increased amount of fuel maintains all of the vaporizers 30 9 at the requisite degree of heat for ignition of the compressed gases. If the ports 19 in the valves be made of the appropriate size, it is not necessary to close the valves when connecting up to the load, but it is 35 preferable to do so to insure against overheating of the pipe connections 27 when running under load.

Now, if it be desired to take the load off of the engine, the lever 7 will be moved in the 40 appropriate direction to disconnect the engine shaft from the driven shaft. When the load has thus been removed from the engine, the governor 2 will speed up, thus causing a diminished supply of fuel to be furnished 45 to the engine cylinders and effecting opening of the valves 18 so that some of the burning gases can pass from all of the cylinders in turn into each of the remaining cylinders so as to maintain all of the vaporizers 50 9 at the requisite temperature for effecting ignition of the successive charges in each cylinder when said charges are compressed by the piston. When the valves 18 are open, the burnt gases are displaced from the hot 55 balls 9 into the valve chambers and thence into the tubing 27 on the up-stroke of the engine pistons. Thus, there is a scavenging action in the hot balls since the gases are forced out through the ports 20 so that the 60 hot gases from the engine cylinders will have access to the entire area of the inner surfaces of the walls of the hot balls and thus maintain them at the proper temperature for ignition of the fuel.

65 From the foregoing it is clear that in this

improved semi-Diesel engine all of the cylinders are in action when the engine is idling as well as when it is under full load and thus with the use of my invention the operation of the engine is evener and less 70 vibratory than is that of former engines of this type.

A valuable feature of the above described construction is the discharging of the flaming gases into the vaporizers toward the jet 75 of fuel oil from the port 14 and opposite to the flow of gases from the piston chamber through the port 10 into the vaporizer so that impact of the flaming gases, oil and compressed gases against one another will 80 take place to finely divide and gasify the fuel and ignite the mixture of finely divided fuel and air.

It is understood that the invention is not limited in its broader aspects to the details 85 of construction shown in the drawings and described above, but that the invention includes such changes and modifications as can be construed as being within the spirit and scope of the appended claims. 90

I claim:

1. In an oil engine, the combination with the cylinders thereof having vaporizers, of tubes connected with the vaporizers respectively, valve chambers for the tubes respectively having outlet ports, valves in the chambers to control the ports, means to operate the valves, and tubing connecting the ports of the valve chambers to one another. 95

2. In an oil engine, the combination with 100 the cylinders and governor thereof, of means controlled by the governor for discharging some of the flaming gases from one cylinder into the other cylinder at higher speeds only of the governor. 105

3. In an oil engine, the combination with the cylinders and governor thereof, of valved connections between the different cylinders, and means operative by increasing speeds of the governor to open the 110 valves and operative by decreasing speeds of the governor to close said valves.

4. In an oil engine, the combination with the cylinders and governor thereof, of vaporizers for the cylinders respectively, 115 tubes connected with the vaporizers respectively, valve chambers for the tubes respectively having outlet ports, valves in the chambers to control the ports, means operative by increasing speeds of the 120 governor to move the valves into port-opening positions and operative by decreasing speeds of the governor to move the valves into port-closing positions, and tubing connecting the ports of the valve chambers to one another. 125

5. In an oil engine, the combination with the cylinders and governor thereof, of vaporizers for the cylinders respectively, 130 tubes connected with the vaporizers respec-

tively, valve chambers for the tubes respectively having outlet ports, valves in the chambers to control the ports, cam means operative by change of speed of the governor, means connecting the valves and cam means to one another, and tubing connecting the ports of the valve chambers to one another.

6. In an oil engine, the combination with 10 one of the cylinders and the governor there- of, of a piston for the cylinder, a vaporizer for the cylinder communicating therewith, means to inject fuel into said vaporizer, a tube connected with the vaporizer to dis- 15 charge some of the burnt gases therefrom, a valve chamber connected with said tube and provided with a port, a valve in the valve chamber to control the port, and means operatively connecting the valve with the gov- 20 ernor.

7. In an oil engine, the combination with one of the cylinders and the governor there- of, of a piston for the cylinder, a vaporizer 25 communicating with said cylinder, and means controlled by the governor for dis- charging some of the burnt gases from the vaporizer at higher speeds only of the gov- ernor.

8. In an oil engine, the combination with 30 one of the cylinders and the governor there- of, of a piston for the cylinder, a vaporizer communicating with said cylinder, and means controlled by the governor for dis- charging some of the burnt gases from the

vaporizer at certain speeds only of the gov- 35 ernor.

9. In an oil engine, the combination with the governor and one of the cylinders there- of, of a piston for the cylinder, a vaporizer 40 communicating with said cylinder, means to inject fuel into said vaporizer, a tube connected with the vaporizer to discharge some of the burnt gases therefrom, a valve chamber connected with said tube and pro- 45 vided with a port, a valve in the valve chamber to control the port, and means opera- tive by increasing speed of the governor to open the valve and operative by decreasing speed of the governor to close said valve.

10. In an oil engine, the combination with 50 a governor therefor of a cylinder, a piston for the cylinder, a vaporizer for the cylinder communicating therewith and provided with a port, means to inject fuel into the vaporizer, a tube leading from the port to 55 discharge some of the burnt gases from the vaporizer, a valve chamber connected with the tube and having a port, a valve to control the last named port, a chamber in com- 60 munication with the last named port, and means operatively connecting the governor with the valve.

Signed at Los Angeles, California, this 18th day of November, 1918.

ALVIN HYDER.
